UNITED STATES PATENT OFFICE.

WILLIAM W. CLARK, OF PORTLAND, OREGON, ASSIGNOR OF ONE-HALF TO IRVING J. BOYCE, OF PORTLAND, OREGON.

TROLLEY-POLE.

1,152,707.

Specification of Letters Patent. Patented Sept. 7, 1915.

Application filed February 16, 1914. Serial No. 819,115.

To all whom it may concern:

Be it known that I, WILLIAM W. CLARK, a citizen of the United States, residing at Portland, in the county of Multnomah and 5 State of Oregon, have invented certain new and useful Improvements in Trolley-Poles, of which the following is a specification.

My invention relates to trolleys that are adapted to be applied to electric cars and 10 like vehicles, and has for its object to provide means for keeping the trolley-wheel in constant contact with the conductor at all times while in use.

A further object of my invention is to 15 provide a device of this kind that is simple in construction, durable, efficient in action, and inexpensive in manufacture.

With these and other useful objects in view, my invention consists of certain novel 20 features of construction, combinations of elements and arrangements of parts to be hereinafter particularly pointed out and specifically claimed.

In order to fully comprehend my invention 25 and the art to which it relates, reference is made to the accompanying drawing, which, taken in connection with the specification forms this application, and of which:—

30 Figure 1 is a top plan view of my invention. Fig. 2 is a side elevation of same, and Fig. 3 is a perspective of a modified form of swivel; a novel form of base would be required with this structure.

35 Now referring to the drawing (in which like characters of reference indicate like parts), the numeral 2 indicates a swivel to which is integrally fastened transverse arms 3, rest 4, and rod 5 in the modified form as 40 shown in Fig. 3. Pivoted to said swivel is a trolley-pole 6 by means of pin 7, while said swivel is revolvably mounted to the roof of a car (represented by line 8) by means of a stud 9, which stud also passes through base 45 10 to which is attached a revolving-pole 11; said revolving-pole serving as a means of turning trolley-pole 6 around to the reverse end of a car; this revolving-pole, however, is only used when a single trolley-pole is attached to a car, and obviously, is unnecessary when a trolley-pole is attached to each 50 end.

Pivotaly fastened to the free end of trolley-pole 6, is a harp 12 which serves as

bearing means for sheave 13 which contacts 55 with the conductor or trolley-wire for purposes well known in the art. It will be noted by observing Figs. 1 and 2 that harp 12 has a semicircular plate 14 extending from the lower portion thereof which serves 60 as a bearing means for the trolley-pole and which also adds strength to said harp. Fastened also to said harp are arms 15, from which pass guide-wires 16 to arms 3; said guide-wires serving to hold sheave 13 in 65 longitudinal alinement with the conductor when trolley-pole 6 is at an angle with relation to roof 8; these guide-wires being of great utility when the car is turning a curve. In order to brace said guide-wires; sleeves 70 17 are provided at points intermediate arms 3 and 15 respectively; said sleeves being integrally fastened to socket 18 which is rigidly secured to trolley-pole 6.

In Fig. 2 is shown a hook 19 secured to 75 roof 8, and serves to prevent lateral movement of revolving-pole 11, while said revolving-pole has attached thereto another hook 20 to engage loop 21 in trolley-pole 6 when said trolley-pole is pulled downwardly 80 by means of cord 22. The front end of the swivel has attached thereto the ordinary form of rods 23, which rods extend through apertures in plate 23^a. I provide, moreover, a fixed head 24^b on the base 10 against 85 which thrusts one end of the spring 24, the other end of the spring thrusting against the plate 23^a. In order to adjust the stretch of the spring, I provide a bolt 24^c extending to the plate 23^a and nut 25 on the outer end 90 of the bolt.

It will be seen from the foregoing that any slight downward movement of the pole 6 will move the left end of the swivel 2 upwardly and to the right, thus increasing 95 the stretch on the spring 24 which consequently resists more strongly and holds the pole in the position shown except when it is forced down by the wire or other causes.

My invention may be constructed of any 100 material and made any size deemed suitable for all the requirements of such a device, and while I have illustrated and described a preferred form of construction and combinations of elements considered essential in 105 materializing the same, I wish to include in this application all mechanical equivalents and substitutes that may be fairly consid-

ered to lie within the scope and purview of my invention as defined in the appended claims.

Having thus fully described my invention so that others skilled in the art to which it relates may be enabled to construct and use the same, what I claim and desire to secure by Letters Patent, is:—

1. The combination with a swivel, of a trolley-pole, means to attach said swivel to a car, a harp pivoted to the free end of the trolley-pole, bearing means in said harp, a sheave mounted on said bearing means, and positively acting devices to aline the harp with a conductor, substantially as described.

2. The combination with a swivel, of means to attach said swivel to the roof of a car, a trolley-pole pivoted to said swivel and arms passing transversely of said swivel, a harp pivoted to the free end of said trolley-pole, bearing means in said harp, and a sheave revolvably mounted on said bearing, transverse arms at the upper side of said harp, wires passing from said arms to the arms of the swivel, said wires serving to

aline the sheave with a conductor, and means to revolve the trolley-pole on the roof of the car, substantially as described.

3. The combination with a swivel, of means to attach said swivel to a car, arms transversely attached to said swivel, a trolley-pole pivotally mounted in said swivel, a harp pivoted to the free end of said trolley-pole, a rest at the lower side of said harp and transverse arms at the upper side, a sheave revolvably mounted in said harp, guide-wires passing from the arms of the harp to the arms of the swivel, sleeves intermediate said arms to brace the guide-wires, means to support said sleeves attached to the trolley-pole, and means to raise and lower said trolley-pole, substantially as described.

In testimony that I claim the foregoing as my own, I hereunto affix my signature in the presence of two witnesses.

WILLIAM W. CLARK.
